CLAIM

The ornamental design of a bead storage cabinet, as shown and described.

DESCRIPTION

FIG. 1 is a front perspective view of a first embodiment of the bead storage cabinet showing my new design;

FIG. 2 is a top view thereof;

FIG. 3 is a front view thereof;

FIG. 4 is a side view thereof;

FIG. 5 is a rear view thereof;

FIG. 6 is a bottom view thereof;

FIG. 7 is a front perspective view of a second embodiment of the bead storage cabinet showing my new design; and,

FIG. 8 is a top view of FIG. 7.

The rear and bottom views of the second embodiment are the same as the rear and bottom views of the first embodiment.
